DISPLAY SIGN

William Donaldson Brown, Fort Thomas, Ky.

Application November 29, 1938, Serial No. 242,984

8 Claims. (Cl. 40—125)

The present invention relates to display signs and is particularly directed to a means of rigidly clamping a sign on a desired surface for the display of advertising matter appearing thereon.

Objects of my invention are: to provide a display sign which may be readily and quickly positioned on or removed from a desired supporting surface; to provide a clamping means which is horizontally and, to a limited extent, vertically adjustable, so that it is capable of holding a sign on supporting surfaces having a number of different sizes and shapes; to provide a novel means of fastening the clamp to a sign; and to provide a novel sign having a number of formed portions which cooperate with the clamping means to bring about many of the advantages obtained by the clamp means.

Other objects will be apparent from the following specification and drawing, in which:

Fig. 1 is a front elevational view of my display sign and shown for illustration as being positioned upon a cash register.

Fig. 2 is a perspective view of my display sign.

Fig. 3 is a cross-sectional view taken on line 3—3 of Fig. 2.

Fig. 4 is a cross-sectional view taken on line 4—4 of Fig. 3.

Fig. 5 is a view similar to Fig. 3 showing another position of my clamping means.

The embodiment of my invention comprises a display sign 6 formed from sheet metal or other suitable material and having a forward depending flange 7, an upstanding advertisement-bearing portion 8 and a horizontal base portion 9 disposed therebetween. The display sign, for the sake of illustration, is shown positioned upon the top of a cash register 10 which has an elongated and substantially square upper portion. My display sign, however, may be positioned upon supporting surfaces of various sizes and shapes because of the specific construction of the clamping means to be hereinafter described and set forth.

The clamping means for the sign is preferably constructed from a flexible or resilient rod or wire 11 which is provided with a central U-shaped portion 12, said portion being provided with elongated and vertically disposed leg portions 13. The rod is also provided with two horizontal straight portions 14 which extend at right angles from and in alignment with the vertical legs of the U-shaped portions, said straight portions terminating in depending feet 15 formed at the extremities thereof. Disposed centrally of and adjacent the rear lower edge of the upstanding portion 8 of the sign is a narrow plate 16 which is

adapted to hold the rod in any vertically adjusted position.

To this end the plate is provided with two spaced hemispherical offsets 17 which engage the legs 13 of the U-shaped portion 12. A bolt and nut 18 runs through the upstanding portion 8 and the plate and is disposed at a point located between the offsets, said bolt and nut being employed as a means of clamping the rod to the sign.

In their normal inoperative position the straight portions 14 of the rod abut the rear surface of the upstanding portion 8 of the sign as indicated by dotted lines in Fig. 3. To place said rod under tension and to adapt it for clamping action, the straight portions 14 are sprung outwardly in an arcuate direction until the feet 15 may be hooked over the rear vertical edge of the supporting surface. A horizontal clamping action is thereby set up between the depending feet 15 and the depending forward flange 7 of the sign. It will be noted that the flange 7 depends a substantial distance beneath the horizontal base portion of the sign and that the feet 15 are substantially elongated. By means of the vertical adjustment provided for the clamp and the elongation of the aforementioned flange and feet, various forms of supporting surfaces may be used for positioning the sign.

The sign may be readily and quickly positioned on or removed from a supporting surface, by merely grasping the display portion of the sign, hooking the feet 15 to the rear vertical wall of the supporting surface and moving the sign forward against the spring tension of the clamping means and then hooking the front flange 7 over the front edge of said supporting surface. By reason of the relatively great arcuate distance through which the arms may be moved, the clamp serves to position the sign upon surfaces having great differences in transverse cross-sectional dimensions.

As illustrated in Fig. 5, my display sign 6 may be positioned on surfaces 19 having a transverse dimension less than the width of the horizontal portion 9 of said sign. To this end bolt 18 of the described sign is loosened to permit the wire to be moved relative to the plate 16 to its lowermost vertical position. The plate is again fastened to the wire, the horizontal straight portions then being well beneath the underside of the horizontal portion of the sign. The straight portions are then manually grasped and moved beneath the sign to a position adjacent the flange 7 (indicated as 20) thus distorting the

wire to a normal unclamped position indicated substantially by said lines 20. The sign is positioned by engaging the feet 15 of the wire and the vertical rear side of the support, moving the sign forward against resilient action of the wire and hooking the flange over the front side of the support. Instead of bending the wire 11 of the clamping means, shown in Figs. 1 and 4, to a position adjacent the flange 7 (indicated as 20 in Fig. 5) to distort it for clamping the sign 6 to surfaces having transverse dimensions less than the width of horizontal portion 9 of the sign, it is contemplated fastening a rod to said sign which has been previously formed to normally 15 occupy the position indicated as 20 in Fig. 5.

What is claimed is:

1. In combination with a display sign having a depending flange, of a clamping means comprising a resilient rod having a central upstanding portion rigidly fastened to the sign, straight portions angularly disposed to and extending from the central portion, and depending feet formed at the extremities of the straight portions.
2. In a display sign, the combination of a sign having a depending flange, and a clamping means comprising a rod having a centrally formed upstanding portion, means for fastening the central portion of the rod to the sign, horizontal straight portions extending from the central portion and depending feet formed at the extremities of the straight portions, said horizontal portions normally abutting the rear surface of the sign and adapted to be sprung outwardly to divergent clamping position.
3. In a display sign, the combination of a sign having a depending flange, and a clamping means comprising a wire having a central upstanding portion, means for fastening the central portion to the sign, horizontal straight portions extending from the central portion, and depending feet formed at the extremities of the straight portions, said horizontal portions being normally adjacent the flange and adapted to be sprung outwardly to operative clamping position.
4. In a display sign, the combination of a sign having a depending flange, and a vertically adjustable clamping means comprising a rod having a vertically formed, elongated, central portion, horizontal straight portions extending from the vertical portion, and depending feet formed at the extremities of the straight portions, and a stationary plate fastened to the sign and adapted to engage the vertical portion of the rod and hold it in any adjusted vertical position.
5. In a display sign the combination of a sheet metal sign having a depending forward flange, an upstanding advertisement-bearing portion and a horizontal base portion therebetween, and a clamping means comprising a resilient wire

having an inverted U-shaped portion located centrally thereof and fastened to the rear of said upstanding portion of the sign, horizontal straight portions extending from the U-shaped portion and depending feet formed at their extremities, said horizontal portions normally abutting the rear surface of the upstanding portion, and adapted to be sprung outwardly to divergent clamping position. 5

6. In a display sign the combination of a sheet metal sign having a depending forward flange, an upstanding advertisement-bearing portion, and a horizontal base portion therebetween, and a clamping means comprising a spring-metal rod having an inverted U-shaped portion centrally 15 thereof, horizontal straight portions extending from the U-shaped portion and depending feet formed at the extremities of the straight portions, and means for fastening the rod to the rear side of the upstanding portion of the sign. 20

7. In a display sign the combination of a sheet metal sign having a depending forward flange, an upstanding indicia-bearing portion, and a horizontal base portion therebetween, and a clamping means comprising a spring-metal rod 25 having an inverted U-shaped portion centrally thereof, horizontal straight portions extending at right angles from the lower ends of the vertical parts of the U-shaped portion, and depending feet formed at the extremities of the straight 30 portions and means for fastening the rod to the rear, lower end of the upstanding portion of the sign and comprising a plate with two spaced, hemispherical offsets formed therein and adapted to engage the U-shaped portion of the rod 35 and means located between the offsets for rigidly fastening the plate to the sign.

8. In a display sign the combination of a sheet metal sign having a depending forward flange, an upstanding indicia-bearing portion and a 40 horizontal base portion therebetween, and a clamping means comprising a spring-metal rod having an inverted U-shaped portion centrally thereof, horizontal straight portions extending at right angles from the lower ends of the vertical legs of the U-shaped portion, and depending 45 feet formed at the extremities of the straight portions and means for adjustably fastening the rod to the rear, lower end of the upstanding portion of the sign and comprising a narrow plate 50 provided with two spaced, hemispherical offsets adapted to engage any desired part of the U-shaped portion of the rod and means located between the offsets and engaging the plate for rigidly fastening the rod to the sign in the desired adjusted position, said horizontal portions 55 normally abutting the rear surface of the upstanding portion and adapted to be sprung outwardly to divergent clamping position.
